UNITED STATES PATENT OFFICE

153,986

DESIGN FOR A FINGER RING

Crescenzo J. Scola, Providence, R. I.

Application August 26, 1948, Serial No. 148,314

Term of patent 14 years

(Cl. D45—10)

To all whom it may concern:

Be it known that I, Crescenzo J. Scola, a citizen of the United States, residing at Providence, in the county of Providence and State of Rhode Island, have invented a new, original, and ornamental Design for Finger Ring, of which the following is a specification, reference being had to the accompanying drawing, constituting a part thereof.

Fig. 1 is a top plan view of finger ring embodying the novel design;

Fig. 2 is a front view thereof; and

Fig. 3 is a side view thereof.

I claim:

The ornamental design for a finger ring, substantially as shown.

CRESLENZO J. SCOLA.
